US0D1047505S

(12) United States Design Patent (10) Patent No.: US D1,047,505 S
(45) Date of Patent: * Oct. 22, 2024

(54) DETACHABLE PLASTIC BAG HOLDER

(71) Applicant: Jinwu Wang, Chuzhou (CN)

(72) Inventor: Jinwu Wang, Chuzhou (CN)

() Term: 15 Years

(21) Appl. No.: 29/948,414

(22) Filed: Jun. 20, 2024

(51) LOC (14) Cl. 08-08

(52) U.S. Cl. USPC D6/566

(58) Field of Classification Search

USPC ..... (57) CLAIM

The ornamental design for a detachable plastic bag holder, as shown and described.

DESCRIPTION

FIG. 1 is a top, front, right side perspective view of a detachable plastic bag holder showing my new design; FIG. 2 is a bottom, rear, right side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of portion 9 in FIG. 1; FIG. 10 is an enlarged view of portion 10 in FIG. 2; and, FIG. 11 is an enlarged view of portion 11 in FIG. 7. The dash-dot-dash broken lines define the boundary of enlarged views and form no part of the claimed design.

1 Claim, 11 Drawing Sheets
